CHARLES EDWARD SOULE, OF BOSTON, MASSACHUSETTS, ASSIGNOR OF ONE-HALF TO
WM. J. KINES, OF NEW BUFFALO, PENNSYLVANIA

PILLOW

Application filed November 17, 1927. Serial No. 233,844.

This invention relates to pillows and is also applicable to seats and back rests.

The invention and its aims and objects will be best understood from the following description taken in connection with the accompanying drawings, of a device embodying one form of said invention selected for the purpose of illustration, it being understood that the invention in its true scope is definitely set forth by the claims.

In the drawings:

Fig. 1 is a top view of one illustrative form of the invention in open position for use as a pillow;

Fig. 2 is an end view of the device illustrated in Fig. 1;

Fig. 3 illustrates an attachment which may be applied when the device is used as a seat;

Fig. 4 is an end view of the device when used as a seat with the attachment shown in Fig. 3 in position;

Fig. 5 illustrates the use of the device as a back rest with the back support in position;

Fig. 6 is a top view of the frame at a collapsed position with the fabric removed; and

Figs. 7 and 8 are sectional details.

In the illustrative embodiment of the invention shown in the drawings, the frame comprises a substantially H-shaped member, 30 consisting of the top rod or member 2, the bottom rod or member 4 extending substantially parallel thereto, and the cross member 6. At the end of the two members 2 and 4 are mounted for swinging movement substantially V-shaped members or rods 8. This may be provided for by any suitable connection for that purpose, the ends of the said members 2 and 4 being herein bent back upon themselves at their ends to form sockets 10 through which branch 12 of said V-shaped members passes, and are held for swinging movement about the axis of branch 12 of said V-shaped members 8. This enables said V-shaped members to be swung about the axis 40 of said branch 12 to bring said V-shaped members into planes substantially perpendicular to the plane of the members 2 and 4, which is the operative position of the device, as more clearly illustrated in Figs. 2, 4 and 5, or into collapsed position, in which the

branches 14 of said V-shaped members lie against the back of said members 2 and 4, which is the collapsed position of the device.

Stop means are provided to maintain said V-shaped members in operative position, that is to say in planes substantially perpendicular to the plane of the members 2 and 4, which is the position they occupy when the device is to be used. This stop means may be of any suitable construction, consisting for example herein of the back turned ends 11 of the branches 12, 12 of the V-shaped members, said ends being turned back in a plane at substantially right angle to the planes of the V-shaped members, so as to contact with the frame member 4 when said V-shaped members are swung into operative position. The H-shaped frame members 2, 4, 6 and the V-shaped members 8 may be made of any suitable material but preferably of metal.

Any suitable metal may be used for the purpose, the V-shaped members particularly being made of resilient metal, so as to afford a yielding supporting action.

The branches 14 of the two V-shaped members 8 constitute resilient members which carry the supporting means which serves as a seat or support for the head or back according to whether the device is used as a seat, a pillow, or a back rest. Herein said support is preferably made yielding or flexible, and to that end consists, in the present embodiment of the invention, of a piece of suitable fabric 16 extending between the branches 14 of the V-shaped members 8 to which it is removably secured in any suitable manner, for example by turning back and sewing the edges of said piece of fabric so as to form hems 18 at the opposite ends thereof through which the branches 14 of the V-shaped members extend, as shown in Figs. 1, 2, 4 and 5. The length of the piece of fabric will preferably be such that the branches 14 will have to be slightly forced toward each other against their natural resiliency, to enter the hems in order that the fabric may be suitably tensioned.

Means are preferably provided to adjust or vary the inclination of the branches 14 relative to the branches 12. Any suitable

means may be provided for that purpose but herein the V-shaped members 8 are made in two parts. The adjacent ends of each part of each V-shaped member is provided with a disc 19, see Fig. 7, each disc being provided upon its inner surface with toothed formations 21, so that when said discs are superposed, their toothed formation will interlock. The discs are provided with a screw threaded central bore 23, engaged by a screw 25 having a knurled edge 27. By loosening the screw the toothed surfaces of the discs can be separated to enable the angular position of the branches 12 and 14 to be changed or adjusted in the desired position, whereupon by tightening the screw the toothed formation on the two discs will be caused to interlock, thus holding the two branches 12 and 14 in adjusted position.

The inclination of the support, herein the fabric 16, and its distance from the frame may thus be varied as desired.

When the device is to be used as a seat by heavy people, the fabric seat may be caused to sag more than desired, due to the resiliency of the V-shaped members. This may be overcome by the use of suitable means herein provided for in the form of a U-shaped bar 20 having its end portions 22, 22 bored to receive the free ends of the branches 14 of the V-shaped members 8. When thus placed in position this bar will prevent the free ends of the branches 14 of the V-shaped members from being drawn toward each other by the weight on the seat, thus preventing too great yielding of the fabric support. The U-shaped bar 20 may be covered with a fabric provided with seams at its opposite edges engaged by the end portions of the U-shaped bar, as shown in Fig. 3. For all ordinary use, however, this U-shaped bar may be dispensed with.

When used as a back rest in bed or in any other situation where there is no back support for the device, the device may be held in suitable position by supporting means herein consisting of a removable square tubular frame 23^a, of a size suitable to the H-shaped member of the frame, and provided at its free edge with clamps 24 to engage the member 2, the lower edge of said tubular frame 23^a resting upon the supporting surface.

Means may be provided in accordance with the invention to vary the tensioning action of the V-shaped members 8 upon the support.

16. Any suitable means may be used for this purpose without departing from the scope of my invention. As an illustrative form of means suitable for this purpose, I preferably, see Figs. 6 and 8, provide the turned back ends 11 of the branches 12, 12 of the V-shaped members 8 with a disc 26 having toothed formations 28 upon their inner surfaces. Upon the adjacent ends of

the branches 12, 12 are provided similar discs 30 with toothed formations 32 upon their inner surfaces. The opposed discs 26 and 30 are bored centrally and the adjacent end portions of the branches 12, 12 are bored axially, said bores being screw-threaded as shown at 34, 36 and 38. Screws 40, 40 having a shoulder 42 and knurled head 44 have screw-threaded engagement with said bores. By loosening the screws 40, 40 and turning the turned-back ends 11, 11 one way or the other relative to the branches 12, 12, the angular position of said turned-back ends may be varied relative to said branches 12, 12, thus increasing or diminishing the tensioning action of the V-shaped members upon the support 16 as will be readily understood. By tightening the screws 40, 40 the turned-back ends 11, 11 are held in their adjusted position.

The device is extremely comfortable, the seat of fabric offering a yielding resilient support, owing to the resiliency of the V-shaped members, this resiliency being secured without the use of any springs or spring formations, by the natural resiliency of the V-shaped members, and the fact that one end of the fabric carrying branches 14 is free. The fabric support yields itself to any position of the head, and owing to the free circulation of air beneath the pillow at all times, the pillow is always cool. It is perfectly sanitary, as the fabric pillow can be removed, and either disinfected or changed at any time. Owing to the adjustability of the height or inclination of the fabric pillow, it can be adapted to the needs or wishes of any individual. By removing the fabric pillow and collapsing the V-shaped members, the whole device can be packed in substantially a single plane, thus taking up very little room, so that it is very easily transported.

The device is exceedingly simple in construction, and can be produced at small cost. There is nothing to get out of order, and the device is practically indestructible.

I am aware that the invention may be embodied in other specific forms without departing from the spirit or essential attributes thereof, and I therefore desire the present embodiment to be considered in all respects as illustrative and not restrictive, reference being had to the appended claims rather than the foregoing description to indicate the scope of the invention.

Claims:

1. A device of the class described, comprising, in combination, a frame; substantially V-shaped resilient members pivotally connected to said frame; a flexible support extending between said V-shaped members and carried thereby when said V-shaped members are in operative position; means to hold said V-shaped members in operative position;

means to vary the relative angular position of the two branches of said V-shaped members; and means to vary the plane of said V-shaped members when they are in operative position.

5. 2. A device of the class described, comprising, in combination, a frame; substantially V-shaped resilient members, each having one of their branches in the plane of the frame and having means connecting said branch thereto for swinging the other and free branch to and from operative position upon said frame; a flexible support extending between the free branches of said V-shaped members and carried thereby when said V-shaped members are in operative position; and rigid means connecting the free ends of the free branches of said V-shaped members when in operative position, for the purpose described.

10. 3. A device of the class described, comprising, in combination, a frame including longitudinal and transverse bars interconnected in a given plane; a plurality of substantially V-shaped members; means pivotally connecting one branch of each of said members to said frame and substantially in the plane of the latter; means to hold said members in operative position wherein their other branches are spaced from the plane of the frame; and a flexible supporting member extending between and positioned by said spaced branches of said V-shaped members.

15. 4. A device of the class described, comprising, in combination, a frame; a plurality of V-shaped members at laterally spaced positions thereon, one leg of each member pivotally connected to the frame substantially in the plane thereof, the other leg, in operative position, projecting angularly from the frame; and a flexible support extending between the projecting legs of said members.

20. 5. A device of the class described, comprising in combination, a frame; hinged substantially V-shaped resilient collapsible carrying members, each having one branch in the plane of and connected to said frame and the other branch free therefrom; a flexible support having means to connect it to and under tension between the free branches of said resilient members; and means to vary the angular relation of the two branches of each of said resilient members thereby to vary the separation of said flexible support from said frame.

25. 6. A device of the class described comprising, in combination, a frame; V-shaped collapsible members, each having one branch in the plane of and connected to said frame; a flexible support extending between and tensioned by the free branches of said resilient members; and means whereby the free branch of a V-shaped member may be moved about the axis of its other branch thereby

variably to adjust the tension of said flexible support.

7. A pillow, comprising, in combination; a flat base, adapted for positioning in a horizontal plane, said base including side portions and a rigid cross-connecting portion; a resilient elongated arcuate carrier member extending upwardly and reversely directly from the base at one end of each of its side portions and so to overlie the base, each in the manner of one branch of a V, said carrier members having, as the other branch of such V, rearward extensions across in the plane of and forming portions of said base, said carrier members being substantially parallel, and each having their upper rearward ends free and spaced vertically from the base; and a flexible head-support extending between and removably carried by said carrying members.

8. In testimony whereof, I have signed my name to this specification.

CHARLES EDWARD SOULE.
